(57) CLAIM

I claim the ornamental design for a vase, as shown and described.

DESCRIPTION

FIG. 1 is a front elevational view of a vase of the claimed design;

FIG. 2 is a rear elevational view of the vase shown in FIG. 1; FIG. 3 is a right side elevational view of the vase shown in FIG. 1;

FIG. 4 is a left side elevational view of the vase shown in FIG. 1;

FIG. 5 is a top plan view of the vase shown in FIG. 1;
